US00D372921S

United States Patent [19]**Ijiri et al.**[11] **Patent Number:** **Des. 372,921**[45] **Date of Patent:** ****Aug. 20, 1996**[54] **CENTRIFUGAL PUMP**

[75] Inventors: **Tomonori Ijiri**, Tokyo; **Nobuhiko Amano**; **Toshihiko Nojiri**, both of Kanagawa-Ken, all of Japan

[73] Assignee: **Terumo Kabushiki Kaisha**, Tokyo, Japan

[**] Term: **14 Years**

[21] Appl. No.: **43,930**

[22] Filed: **Jul. 3, 1995**

Related U.S. Application Data

[63] Continuation of Ser. No. 24,620, Jun. 17, 1994, abandoned.

Foreign Application Priority Data

Dec. 20, 1993 [JP] Japan 5-38191

[57] **CLAIM**

The ornamental design for a centrifugal pump, as shown and described.

DESCRIPTION

FIG. 1 is a top and front perspective view of a centrifugal pump showing our new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.
